FIG.3.

FIG. 4.

Inventor:

CHARLES JOSEPH RHODES,

Patented May 24, 1927.

UNITED STATES PATENT OFFICE.

CHARLES JOSEPH RHODES, OF WAKEFIELD, ENGLAND.

PRESS FOR DRAWING HOLLOW WARE OF SHEET METAL.

Application filed February 20, 1926, Serial No. 89,572, and in Great Britain February 24, 1925.

This invention relates to presses for drawing hollow ware of sheet metal, for instance, vessels or receptacles of considerable depth in one or more stages in a single stroke of the press, whilst maintaining uniform pressure on the work during the entire drawing operation for example as disclosed in Letters Patent Nos. 1,519,833 and 1,561,770.

The object of the present invention is to provide improved operating and controlling mechanism for the drawing or pressure member or members of the stationary die and associated buffer device or devices where the latter are provided.

One feature of the invention comprises improved mechanism for controlling the movement of a drawing or pressure member of the stationary die without the use of a rotary cam, by supporting said pressure member on a reciprocating table, with or without interposed resilient buffer device, and providing locking means for the table comprising one or more wedge elements each supported by a member, movable to release the element, by means of slides having inclined surfaces and moving in an angular path relatively to the axis of the press. The said slides are operated in conjunction with the ram or movable die of the press, in such a manner that movement of the table and consequently of the drawing or pressure member is prevented until the movable die actually makes contact with the work placed on the stationary die, and through same with the drawing member, whereupon the locking means is released, allowing said table and drawing member to recede for effecting the drawing operation.

Another feature of the invention relates to those forms of presses in which a plurality of drawing members, for example two such, are provided for "draw" and "redraw" operations as disclosed in the above mentioned Letters Patent No. 1,561,770, and comprises improved cam and buffer mechanism for said second or redraw member in which the buffer and cam and associated parts are so arranged as to provide a solid resistance when said redraw member acts as a forming member and a resilient pressure when said member acts as a pressure member only.

The invention also comprises other details of construction, arrangement and combination of parts, as set forth in the appended claims and hereinafter fully de-

scribed with reference to the accompanying drawings in which:—

Fig. 1 is a front elevation showing so much of a sheet metal draw press as is necessary for comprehension of the invention, certain parts being in section. Fig. 2 is a side elevation of Fig. 1. Fig. 3 is a detail sectional view showing parts of the mechanism for supporting the table for the first drawing member and Fig. 4 is a sectional detail view of cam and buffer mechanism for the second or redraw member.

To refer more particularly to Figs. 1 and 2 of the drawings 1 designates the frame of the press comprising the base 2 and vertical side members 3 between which latter the ram 4 is vertically slidable, the operating means for the ram being not shown but which may be of any approved type. The ram 4 carries the upper die 5 which co-operates with the lower die 6 supported on a cross frame member 7 the said dies being suitably of the type disclosed in Letters Patent 1,561,770 and 1,561,902 for drawing the hollow ware in two successive stages in a single stroke of the press. The ram is guided in the side frame members 3 by extensions 4^a on the ram extending through slots in said members and to said extensions are adjustably connected rods 8 pivoted to other connecting rods 9 the latter at their lower ends being pivoted to wedge shaped or diamond shaped blocks or slides 10 mounted and guided for sliding movement in guideways 11 in the side members of the base, said guideways having parts 11^a and 11^b arranged in a plane extending in the direction of movement of the ram and an angular portion intermediate said parts (Figure 3).

The inclined faces of the slides 10 co-operate with similarly inclined faces of blocks 12 which also engage in the guideways 11, said blocks being constructed integral with or fixed to a table 13 to extend laterally from opposite sides thereof through the frame members, the table being vertically slidable in the frame and supporting pins or rods 6^a carrying the outer draw ring or member 6^b of the lower die. The table is normally supported in position with the drawing member 6^b in a plane with the top of the stationary die by abutments in the form of slides 114 for the releasable engagement of the blocks 12, said slides being guided for horizontal transverse movement in guides 15 on the frame and having at the

center opposite bridge pieces 16 for the engagement and passage therebetween of the diamond shaped slides 10.

Thus so long as the ram 4 is in its upper position and the dies are separated as shown in Fig. 1 the table 13 and consequently the drawing member 6^b are maintained in normal elevated position but at the correct movement, that is to say when the upper movable die 5 makes contact with the work on the lower die 6 by descent of the ram, the diamond slides 10 travel from the path 11^a of the guideways 11 through the angular portion of the guideways to the path 11^b of said guideways and during this movement co-operating with the bridge piece 16 of the abutment slides 14 to move said slides transversely. This horizontal movement of slides 14 releases the wedge blocks 12 and on continued downward movement of the ram consequently permits descent of the table and with the latter the descent of the draw ring 6^b to permit the drawing operation, or in the embodiment of the present machine the first stage of such drawing operation. The diamond slides 10 all the while remain below the blocks 12 and as the ram again rises after the end of its downward stroke the said slides will lift the blocks 12 in path 11^b and with them the table and draw ring 6^b and will also move back the transverse slides 14 so that the latter are caused to again support the blocks, and the table and become locked, the diamond slides then continuing their upward travel in path 11^a until the ram reaches its uppermost position ready for a new stroke. It should be noted that the supporting stress of the table as it descends is taken by two inclined faces viz 10^a on the diamond slide and 12^a on the wedge block which cannot slip due to the fact that both are guided in a common path 11^b which laterally supports the slide 10 and block 12 in their movements.

So far the detail description has related only to the control of a single draw member 6^b and in presses having only one such member for single drawing operations the control of said drawing member is terminated by the means described, but in forms of presses in which the drawing operation is performed in a number of stages by a plurality of draw members or rings, two such being shown in the present embodiment, it is also necessary to control the said second draw member and the invention further comprises improved means for this purpose.

The second draw or "redraw" member is designated 6^c in Fig. 1 and its supporting pins 6^a extend downwards through the outer block of the lower die and are supported by a block 17 or equivalent which is carried by a stem or spindle 18 adjustably mounted on a screw spindle 19 tapped into a casting or

block 20 slidable relatively to the table 13 and which carries a roller 21 bearing on the periphery of a controlling cam 22. This cam is loosely mounted on a shaft 23 on which is rigidly mounted a disc or plate 24, 70 adjustable connections as by bolts and slots 25 being made between the cam and disc in order that the angle of the latter on the shaft may be varied to control the time of operation of the redraw member 6^c relatively to the first draw member 6^b. The shaft 23 is oscillated by means of pinions 26 thereon engaging racks connected to the table 13.

The casting 20 aforesaid is associated with 80 a buffer device which is arranged to give a solid support to the redraw member 6^c during the first drawing operation, that is to say, whilst the first draw member 6^b is receding and the redraw member is acting as a former, and also a resilient pressure support to the redraw member during the second drawing operation, that is to say, when it is receding and acting as a pressure member only.

For this purpose the buffer device comprises a resilient or rubber cushion 26^a surrounded by a metal plate 27 adapted to have a limited vertical movement relatively to the casting 20 and the pressure of said cushion may be varied by a plate 28 below the cushion under the action of screwed washers 29. The spindle 19 is free in the casting 20 but is screwed into plate 27 and held by a nut 27^a.

The cam 22 is of special contour as indicated in Fig. 4 which permits a telescopic action of the plate 28 to come into effect and the cushion to expand to take the required pressure for drawing such pressure being adjusted by the washers 29.

The cushion is thus held between the two plates 27 and 28 and when the redraw member 6^c is being used as a forming member the cam presses the cushion through the roller 21 and casting 20 and through the spindle 18 offers a rigid resistance to the redraw member (see Fig. 4). When however the roller 21 comes to a slightly dropped position 24^a of the cam preceding the position 22^a controlling the redraw movement of the pressure member the casting 20 falls allowing the rubber cushion 26^a to expand so that at the moment the redraw member actually functions as a pressure member (redraw operation commencing) the cushion is permitted to exert resilient pressure on the redraw member and consequently on the work which will be sufficient for drawing purposes.

I do not limit myself to the exact construction arrangement or combination of parts hereinbefore described or illustrated in the drawings since the same may be varied within limits presented by the appended

claims without departing from the spirit of the invention.

What I claim as my invention and desire to secure by Letters Patent of the United

5 States is:—

1. In a draw press, a die embodying a stationary member and a member movable relative thereto, a movable die co-operating with the stationary member of the 10 first die to effect a drawing of work placed relative to said die, a movable carrier for the drawing member embodying a slidably mounted element, a slide movable transversely of the slidably mounted element of 15 the drawing member carrier and normally positioned for engagement by said element to hold the drawing member carrier against movement, and a slidably mounted member operating in unison with the movable die to co-operate with said transversely movable slide to move the same out of engagement with the slidably mounted element of the 20 carrier to release the carrier and permit the carrier with the drawing member to participate in the movement of the movable die and recede relative to its co-operating stationary die member to effect the drawing of 25 the work over said latter member.

2. In a draw press, a die embodying a 30 fixed member and a drawing member movable relative to the fixed member, a movable die co-operating with said fixed die member to effect a drawing of work placed on said fixed die member, a movable table adapted 35 to support the drawing member, blocks connected with and normally supporting said table, slides movable transversely of and normally engaged by said blocks to support the table, and slidable members operating 40 in unison with the movable die and have movement in an angular path relative to the axis of the press, said members having inclined surfaces to co-operate with said transversely movable slides to move the 45 same out of supporting engagement by the blocks to release the table and move said inclined surfaces into supporting engagement with the blocks and permit of receding movement of the table with the drawing 50 member in unison with the movable die.

3. In a draw press, a stationary die and a drawing member movable relative thereto, a movable die co-operating with said stationary die to effect a drawing of work 55 placed on said latter die, a table on which the drawing member is supported, blocks connected to and supporting the table slidably mounted to have movement in the direction of the movable die and having an inclined face extending at an angle to its direction of movement, slides movable 60 transversely to the movement of the blocks for engagement by and releasably support the blocks, slidable members operating in 65 unison with the movable die and having in-

clined surfaces, and guideways for said slideable members having a part extending in angular relation to the axis of the press for engagement of the inclined surface of said members to impart movement thereto in angular direction to the movement of the movable die and during said movement co-operate with the transversely movable slides to move the same out of engagement with the blocks to release the table and co-operate with the 70 inclined face of the blocks to support and permit the table to recede with the drawing member, and said engagement of the slidable members with the blocks also acting to return the table to normal position after 75 the drawing operation.

4. In a draw press, a stationary die and a drawing member movable relative thereto, a movable die cooperating with said stationary die to effect a drawing of work 80 placed on said latter die, a carrier for the drawing member movable in the direction of the movable die, said table being arranged with laterally extending blocks having a face inclining to the direction of movement of the table, slides movable transversely of and for engagement by the table blocks to normally support the table, and slides movable in unison with the movable 85 die and having inclined surfaces to co-operate with said transverse slides to move the same out of engagement with the table blocks, and release the table when the movable die contacts with the work on the stationary die, and co-operate with the carrier blocks to permit said carrier with the drawing member to recede from the fixed die member in unison with the movement of 90 the movable die.

5. In a draw press, a stationary die and a drawing member movable relative thereto, a reciprocating die to co-operate with said stationary die to effect a drawing of work placed on said latter die, means movable 100 in the direction of the reciprocating die adapted to carry the drawing member arranged with parts having a face inclined to the direction of movement of said carrying means, slides movable transversely of the movement of said carrying means and normally positioned for engagement of the parts having the inclined face to support the table, and slides operating in unison with the reciprocating die and having inclined surfaces to co-operate with said transversely 110 movable slides to move the same out of supporting position for and release the carrying means to permit the latter with the drawing member to recede from the fixed die member in unison with the movement of the reciprocating member.

6. In a draw press, a stationary die and a drawing member movable relative thereto, a reciprocating die co-operating with said stationary die to effect a drawing of work 120

placed on said latter die, movable means adapted to carry the drawing member arranged with parts having a face inclined to the direction of movement of said carrying means, slides movable transversely of the movement of and normally engaged by the parts of the carrying means having the inclined face to support said drawing member carrying means, and slides operating in unison with the reciprocatory die and having opposite inclined surfaces, said slides engaging in guideways having a part extending in angular relation to the axis of the press and co-operating with said transversely movable slides to move the same out of engagement with the parts having the inclined face of the drawing member carrying means to release said carrying means and co-operating with the inclined face of said parts of the drawing member carrying means to support and permit said carrying means to participate in the movement of the reciprocatory die when said die contacts with the work on the stationary die, and said slides also acting to return the carrying means to normal position and the transversely movable slides to supporting position for the drawing member carrying means after the drawing operation.

7. In a draw press having a stationary die provided with a plurality of relatively movable receding drawing members, and a movable die cooperating with said drawing members to effect a drawing operation in a succession of stages in a single stroke of the press, the combination of a movable table adapted to support one of said drawing members, holding means for said table operating in unison with the movable die and acting to release said table when the movable die engages the work on the stationary die and cam and resilient buffer means whereby a solid resistance is provided for a successively acting drawing member when the same acts as a former and a resilient resistance is provided therefor when said member acts as a drawing member.

8. In a draw press having a stationary die provided with two relatively movable and successively acting drawing members for effecting "draw" and "redraw" operations on the work during a single stroke of the press, the combination of a reciprocatory table adapted to support the "draw" member during the draw operation, holding means for said table operating in unison with the movable die adapted to maintain same stationary until the movable die engages the work on the stationary die, cam and resilient buffer means whereby a solid resistance is provided for the "redraw" member when the same acts as a former and a resilient resistance when said member acts as a pressure element during a redrawing operation, said buffer means being fully compressed during the "draw" operation and permitted freedom of resilient action during the "redraw" operation by the contour of the cam.

9. In a draw press, a die embodying a fixed member and a drawing member movable relative to the fixed member, a ram carrying a die reciprocatory toward and away from the first die to co-operate with the latter to effect a drawing of work placed relative thereto, a carrier for the drawing member movable in the direction of movement of the ram, abutment means movable transversely of the movement of the carrier for the drawing member adapted for the releasable engagement and support of the carrier, and means operative in unison with the ram to move the abutment means out of carrier supporting position and support and permit movement of the carrier in unison with the ram during the drawing operation and participate in the receding movement of the ram to return the drawing member to initial position and move the abutment to carrier supporting position during said latter movement.

In witness whereof I have signed this specification.

CHARLES JOSEPH RHODES.
